PAPER MAKING MACHINE

William R. McPherson and Peter J. Van Norden,
Otsego, Mich.

Application November 20, 1933, Serial No. 698,774

24 Claims. (Cl. 92—43)

The main objects of this invention are:

First, to provide a paper making machine for making box board and the like having a crosswise tensile strength comparable to its lengthwise tensile strength.

Second, to provide a machine of this character having means for controlling the flow of stock across the opposite side faces of the cylindrical mold.

Third, to provide a vat or box having means associated therewith for thoroughly and effectively crossing the fibers on the cylindrical mold, which results in the formation of a sheet of substantially uniform strength and stiffness in all directions.

Objects relating to details and economies of our invention will appear from the description to follow. The invention is defined and pointed out in the claims.

A structure which is a preferred embodiment of our invention is illustrated in the accompanying drawings, in which:

Fig. 1 is a fragmentary top plan view of a paper making machine embodying the features of our invention.

Fig. 2 is a fragmentary end elevation, a portion of the box or vat being broken away and shown in section.

Fig. 3 is a fragmentary opposite end elevation of the box, portions being broken away and shown in section.

Fig. 4 is an enlarged transverse section on a line corresponding to line 4—4 of Figs. 1, 5, and 6.

Fig. 5 is a fragmentary horizontal section on line 5—5 of Fig. 4.

Fig. 6 is a fragmentary longitudinal vertical section on a line corresponding to line 6—6 of Figs. 1, 3, and 4.

Fig. 7 is an enlarged fragmentary longitudinal vertical section on a line corresponding to line 7—7 of Figs. 1, 3, and 4.

In the embodiment of our invention illustrated in the drawings, numeral 1 indicates a pulp vat or box having side walls 2, 2 and ends walls 3, 3. The vat is adapted to contain a mixture of paper pulp stock and water, hereinafter referred to as stock. The forming cylinder 4 is disposed between and rotatably supported by the end walls 3, 3. The cylinder itself is of the conventional screen type and therefore forms no part of our invention. It is arranged for coaction with a felt belt 5 which passes around the couch roll 6 disposed in such relation to the top of the cylinder 4 that the belt contacts with the cylinder and picks up the fibers from the cylin-

der, the cylinder being rotated by such contact.

The end walls of the vat are provided with white or waste water gravity outlets 7, 7 opening to the interior of the cylinder at the upwardly moving side thereof. Such outlets are controlled by means of vertically adjustable weirs 8, 8, respectively, which control the level of the white water. The latter flows over the weirs and downwardly through the vertical passages 9, 9 which are connected to the sewer drain or to a save-all (not shown).

The end walls are also provided with stock suction outlets 10, 10 opening to the interior of the cylinder at the bottom thereof. These stock outlets are connected to the main stock outlet 11 by means of the end conduits 12 and 13, respectively, the latter in turn being connected by the longitudinal outlet passage 14 disposed in one of the lower corners of the box. At one end, the passage is provided with a clean-out closure 15. The main stock outlet 11 is connected to a recirculating pump providing suction means for the stock outlet 10, 10.

Stock inlets 16, 16 are provided in the end walls at opposite sides of the cylinder, there being one inlet in each end wall and the inlets being arranged in diagonally opposite corners of the box. The stock inlets 16, 16 are connected to the common stock supply 17 by means of the central T-coupling 18 and pipes 19, 19 arranged under the vat. The main stock inlet 17 is connected to the stock tank. The end walls are also provided with stock gravity outlets 20, 20 opposite the stock inlets. Vertically adjustable weirs or gates 21, 21 are associated with the overflow stock gravity outlets for controlling the level of the pulp in the vat. The stock outlets 20, 20 are connected to the main stock outlet 11 by means of the end passages 12 and 13, such end passages being in communication with each other through the longitudinal passage 14, as pointed out above.

Horizontal shelves or flow ledges 22, 22 are disposed in opposite sides of the box adjacent the side walls at the lower level of the stock inlets, the ledges having their inner edges 23, 23 spaced from the cylinder 4 and biased toward the same from the stock inlets. The ledges act to direct the flow of stock, directing the fibers toward the cylinder uniformly of the length thereof, resulting in a uniform sheet, or "levels" the sheet, as it is called. Curved walls 33, 33 extend from the ledges and under the cylinder, as shown, to the clean-out 34.

Adjustable flow directors 24 and 25 are pivoted

110

at the sides of the stock inlets for controlling the direction of the stock flow as desired. Bolts 26 are provided for securing the flow directors in adjusted position.

5 Baffles 27 are associated with the inner edges of the flow ledges and have their upper edges 28 downwardly inclined toward the same from the stock inlets acting to provide channels of gradually diminishing depth. The baffles direct the 10 settling fibers of the stock toward the center of the vat and prevent them from settling over the edge of the ledge near the stock inlet.

The flow of stock is in opposite directions on opposite sides of the cylinder, the amount of water circulating is controlled by the arrangement 15 of the gravity outlets and the fibers are all kept in suspension in the stock. This prevents bunching of the fibers. In general, our arrangement tends to give a very uniform formation of fibers 20 on the cylinder. Further, it will be observed that by the use of adjustable gates at the gravity outlets there will be just as much water in circulation on a heavy weight sheet as on a light weight sheet, which is very desirable in keeping the fibers 25 in suspension.

Tests on board made with the conventional vat show that the tensile strength crosswise is only 30 25% of the tensile strength lengthwise. Board made with our improved vat has a tensile strength crosswise of 65% of the tensile strength lengthwise. Substantial uniformity of stiffness and 35 tensile strength of the sheet is obtained in all directions. This obviates the necessity of the specification by the box maker for grain a certain 40 way of the sheet. Very substantial saving is effected in the furnish inasmuch as less sulphite pulp is required to give the desired bending qualities 45 of the sheet in either direction. Further, less kraft and jute furnish are required to give the desired Mullen test. It will be also evident to those skilled in the art that great savings are effected in the manufacture of boards such as 50 carton stock, box stock, bottle cap, and in fact, any grade where it is advantageous to get uniform tensile strength in all directions as well as high Mullen test.

Our improved vat can be installed in the same space or in less space than is required by the commonly used type of vat, which is a very desirable 55 feature as it saves the mill from changing the felt framework. Also, the same cylinders and couchers now in use can be used with our improved vat. In general, our improved vat is very easily adapted for use in place of the ordinary 60 type of vat.

Our improved vat acts to cross the fibers on the cylinder mold quite thoroughly and results in a sheet of approximately uniform strength and stiffness in all directions.

65 We have illustrated and described our improvements in an embodiment which we have found very practical. We have not attempted to illustrate or describe other embodiments or adaptations, as it is believed this disclosure will enable those skilled in the art to embody or adapt our improvements as may be desired.

Having thus-described our invention, what we claim as new and desire to secure by Letters Patent, is:

70 1. In a paper making machine of the class described, the combination of a pulp vat or box comprising side and end walls, a cylinder mold disposed between and rotatably supported by said end walls, waste water gravity outlets in the end 75 walls opening to the interior of the cylinder mold

adjacent the top thereof, stock suction outlets in the end walls opening to the interior of the cylinder mold at the bottom thereof, stock inlets in the end walls at opposite sides of the cylinder mold, there being one inlet in each end wall and the inlets being arranged in diagonally opposite corners of the box, overflow stock gravity outlets in the end walls opposite the stock inlets, means for adjusting the level of said waste water and overflow stock gravity outlets, horizontal flow ledges disposed in opposite sides of the box adjacent the side walls adjacent the lower level of the stock inlets and having their inner edges spaced from the cylinder mold and biased toward the same from the stock inlets, vertical adjustable flow directors at the sides of the stock inlets, and baffles associated with the inner edges of said ledges and having their upper edges downwardly inclined from the stock inlets.

80 2. In a paper making machine of the class described, the combination of a pulp vat or box comprising side and end walls, a cylinder mold disposed between and rotatably supported by said end walls, waste paper gravity outlets in the end walls opening to the interior of the cylinder mold adjacent the top thereof, stock suction outlets in the end walls opening to the interior of the cylinder mold at the bottom thereof, stock inlets in the end walls at opposite sides of the cylinder mold, there being one inlet in each end wall and the inlets being arranged in diagonally opposite corners of the box, overflow stock gravity outlets in the end walls opposite the stock inlets, suction means connected to said stock suction outlets, horizontal flow ledges disposed in opposite sides of the box adjacent the side walls adjacent the lower level of the stock inlets and having their inner edges spaced from the cylinder mold and biased toward the same from the stock inlets, vertical adjustable flow directors at the 90 sides of the stock inlets, and baffles associated with the inner edges of said ledges and having their upper edges downwardly inclined from the stock inlets.

95 3. In a paper making machine of the class described, the combination of a pulp vat or box comprising side and end walls, a cylinder mold disposed between and rotatably supported by said

100 end walls, waste water gravity outlets in the end walls opening to the interior of the cylinder mold adjacent the top thereof, stock suction outlets in the end walls opening to the interior of the cylinder mold at the bottom thereof, stock inlets in the end walls at opposite sides of the cylinder mold, there being one inlet in each end wall and the inlets being arranged in diagonally opposite corners of the box, overflow stock gravity outlets in the end walls opposite the stock inlets, horizontal flow ledges disposed in opposite sides of the box adjacent the side walls adjacent the lower level of the stock inlets and having their inner edges spaced from the cylinder mold and biased toward the same from the stock inlets, and baffles associated with the inner edges of said ledges and having their upper edges downwardly inclined from the stock inlets.

105 4. In a paper making machine of the class described, the combination of a pulp vat or box comprising side and end walls, a forming cylinder, waste water gravity outlets in the end walls opening to the interior of the cylinder at the side thereof, stock suction outlets in the end walls opening to the interior of the cylinder at the bottom thereof, stock inlets in the end walls at opposite sides of the cylinder, there being one inlet 110

- 5 associated with the stock inlet ends of the flow 80 flow ledges, stock outlets opposite the inlets, and
ledges and having their upper edges inclined away 85 white water discharge connections to the inside
from the stock inlets, and forced circulating discharge connections to the inside of the cylinder
5 operatively associated with the stock outlets, the 90 cylinder at each end thereof.
10 20. In a paper making machine of the class
described, the combination of a vat, a forming 95 cylinder within said vat, the vat having a curved
bottom disposed in a biased relation relative to 100 the axis of the cylinder and including horizontal
flow ledge portions at the top of the curved portions,
15 stock inlets disposed at diagonally opposite 105 corners of the vat to discharge above the flow
ledges, stock outlets opposite the inlets, and
forced circulating discharge connections to the
inside of the cylinder operatively associated with
the stock outlets, the stock supply and said stock
inlets.
20 21. In a paper making machine of the class
described, the combination of a vat, a forming 90 cylinder within said vat, stock inlets disposed
at diagonally opposite corners of the vat, stock
outlets opposite the inlets, and forced circulating
discharge connections to the inside of the
cylinder operatively associated with the stock
outlets, the stock supply and said stock inlets.
25 22. In a paper making machine of the class
described, the combination of a vat, a coacting 100 forming cylinder disposed within the vat, stock
inlets disposed at diagonally opposite corners of
the vat, stock outlets disposed opposite the inlets,
white water discharge connections opening to
the inside of the cylinder at both ends thereof,
30 the stock outlets being connected to
said white water discharge connections, and a
circulating means operatively associated with
said white water discharge connections.
35 23. In a paper making machine of the class
described, the combination of a vat, a forming 110 cylinder within said vat, the vat having a curved
bottom disposed in a biased relation relative to
the axis of the cylinder and including horizontal
flow ledge portions at the top of the curved
40 portions, stock inlets disposed at diagonally opposite
corners of the vat to discharge above the
flow ledges, stock outlets opposite the inlets,
baffles associated with the flow ledges and having
45 their upper edges inclined away from the
stock inlets, and white water discharge connections
to the inside of the cylinder at each end
thereof.
50 24. In a paper making machine of the class
described, the combination of a vat, a coacting 120 forming cylinder disposed within the vat, stock
inlets disposed at diagonally opposite corners of
the vat, stock outlets disposed opposite the inlets,
55 and white water discharge connections opening to
the inside of the cylinder at both ends thereof.
130
